(57) CLAIM

The ornamental design for a compact fluorescent light with built-in, tea-light candle holder, as shown and described.

DESCRIPTION

FIG. 1 is a perspective front, right side and bottom view of a compact fluorescent light with built-in, tea-light candle holder, showing the first variant of my design;

FIG. 2 is a front view thereof;

FIG. 3 is a right side view thereof;

FIG. 4 is a rear view thereof;

FIG. 5 is a left side view thereof;

FIG. 6 is a bottom view thereof;

FIG. 7 is a top view thereof;

FIG. 8 is a perspective front, right side and bottom view of the second variant of my design;

FIG. 9 is a front view of the second variant of my design;

FIG. 10 is a right side view of the second variant of my design;

FIG. 11 is a rear view of the second variant of my design;

FIG. 12 is a left side view of the second variant of my design; and,

FIG. 13 is a top view the second variant of my design; the bottom view of the second variant of my design being a same image as in FIG. 6.

The dotted line disclosure of a tea-light candle in FIG. 2 is for illustrative purposes only and forms no part of the claimed design.
